UNITED STATES PATENT OFFICE.

JOHN B. RUSS, OF SHELTON, CONNECTICUT, ASSIGNOR TO THE BASSETT METAL GOODS COMPANY, INC., OF SHELTON, CONNECTICUT, A CORPORATION OF CONNECTICUT.

DESIGN FOR A BAG-CATCH TOP PLATE.

Application filed March 13, 1928. Serial No. 25,819. Term of patent 14 years.

To all whom it may concern:

Be it known that I, JOHN B. Russ, a citizen of the United States, residing at Shelton, county of Fairfield, State of Connecticut, have invented a new, original, and ornamental Design for a Bag Catch Top Plate, of which the following is a specification, reference being had to the accompanying drawing, forming a part thereof.

The drawing shows a perspective view of a bag catch top plate showing my new design, with portions of the base member used therewith indicated in dotted lines.

I claim:

The ornamental design for a bag catch top plate as shown.

JOHN B. RUSS.
